VARIABLE ELECTRICAL RESISTANCE
DEVICE

Louis W. Thompson, Schenectady, N. Y., assignor
to General Electric Company, a corporation of
New York

Application September 13, 1934, Serial No. 743,850

22 Claims. (Cl. 201—51)

My invention relates to variable electrical resistance devices and more particularly to compressible type variable electrical resistance devices.

5 This application is a continuation-in-part of my application Serial No. 604,954, filed April 13, 1932 and assigned to the assignee of the present application.

10 Compressible type variable resistances, of which the well known carbon pile resistance is perhaps the best known example, possess a number of distinct operating advantages. Among these advantages are the ability of such variable resistance devices to vary their resistance 15 in infinitely small steps and their ability to do this without the use of circuit making and breaking contacts. Heretofore, however, these devices have had certain inherent operating limitations which have militated against their 20 more wide-spread use. These operating limitations are those which affect the operation of the devices when they are operating at their maximum and minimum resistance limits. Thus it has been found that at the maximum 25 resistance limits of the operation of compressible pile resistances, these devices become relatively unstable and extremely sensitive to vibration, due to the fact that the pressure tending to force the contact faces of the units of the piles together is comparatively low. In their other extreme condition of operation, that is to say, when it is desired to have the pile resistances have a minimum resistance, it has been found that even when an excessively high pressure 30 is applied to the pile resistances, they will have an appreciable resistance. For greatest usefulness, however, it is desirable that these resistances be able to have a minimum resistance value which is substantially zero. Heretofore, 35 it has only been possible to have this result by using a special external contact arrangement for short-circuiting the resistance when full pressure is applied thereto.

40 In accordance with my invention I provide a compressible resistance which is built up of novel units and which is stable and satisfactory in operation at its maximum resistance values and which has a substantially zero resistance at its other extreme limit of operation. One way that 45 I achieve these desired results is by building up a compressible pile resistance from a plurality of units, some of which may be elastic and deformable in such a manner that when full pressure is applied to the device the electrical resistance 50 through the units comprising the device

is reduced substantially to zero, while when the pressure applied to the device is low, corresponding to the maximum resistance position of the device, the engagement of the elements comprising the device will be sufficiently firm to insure stable and reliable operation at this position. I obtain a part of the change in resistance by constructing the units with high and low specific resistance sections, as will be more fully described hereinafter.

5 10 An object of my invention is to provide an improved type of compressible resistance.

Another object of my invention is to provide a compressible pile resistance having an increased range of resistance variation.

15 A further object of my invention is to provide a novel unit for compressible type resistances.

An additional object of my invention is to provide a compressible pile type resistance which has a substantially zero resistance through the 20 units comprising the pile when full pressure is applied thereto.

25 My invention will be better understood from the following description taken in connection with the accompanying drawing and its scope will be pointed out in the appended claims.

In the drawing, Fig. 1 is a side elevation of a particular type of resistance unit for my compressible resistance; Fig. 2 is a plan view of the unit shown in Fig. 1; Fig. 3 is an elevation, partly 30 in section, of a manually controllable compressible pile resistance employing resistance units of the type illustrated in Figs. 1 and 2; Fig. 4 illustrates diagrammatically how a compressible pile resistance may be used as an element of 35 an automatic regulator; Fig. 5 is a sectional view of a modified unit; and Fig. 6 is a plan view of the unit shown in Fig. 5.

40 In Figs. 1 and 2, I have illustrated one embodiment of my invention in a particular form of resistance unit which is adapted for use in compressible pile resistances. An important distinguishing characteristic of this unit is that it is composed of a resilient, or elastic, resistance material 1. One such material which is suitable 45 for use is carbon, although my invention is not limited to any particular type of material, and metal plates, or discs, having an oxide coating may be employed, if desired. It is also important that the adjacent, or cooperating, contact 50 faces of the units comprising my compressible resistance be not normally parallel and one way of insuring this is to make at least one of the opposite contact faces of each unit curved. As shown in Fig. 1, I have shown both the top and 55

bottom contact faces of the unit to be dished inwardly, or concave, so that the effective thickness of the unit, as measured between parallel planes, represented in one instance by the lines 2 and 3, varies, it being thickest at its ends and 10 thinnest at its center. However, my invention is not limited to such a shape and as the description of my invention proceeds it will become obvious to those skilled in the art that the top or bottom, or both, contact surfaces may be any 15 shape.

I connect electrically, by means of a comparatively low resistance path, the portions of the top and bottom faces of the unit which are at its 20 thinnest points. This effective short-circuiting may be done in any convenient manner and, as shown, I employ a coating 4 of metal forming a ring about the thinnest portion of the unit. In effect, the coating 4 forms a relatively low resistance section of my unit. The metal coating 25 4 may be applied in any suitable manner, such as by electroplating or by pressing thin metal foil on the unit, although I have found that best results are obtained when the metal is volatilized and is sprayed onto the material 1 by pressure through a nozzle. Any suitable metal may be employed and I have found that good results are obtained when silver is used.

As I intend that the unit be flexed when pressure is applied thereto, it is desirable to cut certain portions out of the unit and I have found that particularly good results are obtained when V-shaped notches are cut out of the ends of the 30 unit between its top and bottom faces. These notches are illustrated at 5 in Fig. 1.

As shown in Fig. 2 the unit is of an elongated rectangular shape, but this is not important and it may have any desired shape.

In the manually controlled compressible pile 40 resistance illustrated in Fig. 3 there is provided a suitable base 6 on which are mounted end supports 7, for the pile, and these supports are provided with suitable binding posts 8. The base 6 is preferably made of insulating material while supports 7 are made of any conducting material. Between the supports is mounted a tubular insulating member 9. Fitted loosely in this container are a plurality of the units shown in 45 Figs. 1 and 2 and these units are so arranged in the container that their contact faces are mounted for cooperation and are adjacent each other. A suitable means, in the form of a hand screw 50 10, is employed for applying pressure to the unit.

In operation, as the hand screw 10 turns in a 55 way to increase the pressure on the pile the tips of the units will first come into contact. By giving the screw 10 a slight turn all of the units may be held firmly together due to the slight 60 flexing of the legs of the V-shaped notches. The current path will be from the right-hand binding post through support 7, through screw 10, a conducting plate 11, and then in a zigzag path through all of the units to the other supporting member 7 and to the other binding post. The 65 resistance will be relatively high for three separate distinct reasons. These are that the electrical path is considerably longer than the shortest distance between the end units because of the fact that the conducting path is zigzag in 70 shape; the area of contact of the units is relatively small as just the tips of the units are in contact; and as the units are only very slightly compressed, and as they are composed of carbon, the resistance of the material itself will be high.

Of course, if a material whose resistance does not change with pressure is used, the latter factor will not be present. If the pressure on the pile is increased, by continuing to turn the screw 10, the units will flex further and the points of contact of the units will move toward their centers, thus simultaneously shortening the conducting path, increasing the contact area of the units, and decreasing the resistance of the units due to the increase in pressure applied thereto. When 10 full pressure is finally applied to the pile substantially all of the cooperating contact faces of adjacent units will be in contact with the result that the sections, or portions, 4, of the units will be in contact thereby providing a substantially 15 zero resistance path through the entire pile.

From the above description of the operation of a particular embodiment of my invention it will be seen that, in principle, the operation of my invention depends upon the use of at least 20 one resilient, elastic or deformable element, which may or may not be a resistance element, cooperating with a resistance element, which may or may not be deformable, the resistance element having a substantially zero resistance section between opposite contact faces, which section is arranged to come into engagement with the adjacent element when full pressure is applied to the elements.

I am aware that the carbon pile units are known in which either the top, or bottom, or both of these surfaces are dished and which have parallel-sided notches cut in the ends of these units between the top and bottom surfaces. However, I have found that by making these notches V-shaped a considerably improved operation results because with such notches the unit is better adapted to withstand flexing and considerably less breakage occurs.

In the automatic regulating arrangement shown in Fig. 4 a compressible pile resistance, composed of my units, is connected in series with the field winding 12 of a generator 13 which is connected to energize a circuit 14. A voltage responsive electromagnet 15 which is connected across the circuit 14 is arranged, by means of a suitable linkage 16 to control the pressure on the pile 11. In this manner when the voltage of the generator 13 increases above a predetermined normal value the pull of the magnet 15 increases in such a manner that this magnet operates to reduce the pressure on pile 11 thereby increasing its resistance and thus decreasing the current in the field winding 12. This decreases the voltage of the generator 13 and returns it to normal. Similarly, if the voltage of generator 13 decreases below normal for any reason the magnet 15 will have its pull weakened, thereby to increase the pressure on the pile 11 with the result that its resistance is decreased and the current through the field winding 12 is increased, thereby increasing the voltage of the generator 13. This will continue until the voltage returns to normal.

In the modification shown in Figs. 5 and 6 the resistance between the opposite contact faces of the middle portion of the unit is short-circuited by an electrical conductor in the form of a flat-headed rivet 17 passing through the unit and having a washer 18 riveted thereto. Parts 17 and 18 may be made of silver, if desired, and in a pile comprising a plurality of the units shown in Figs. 5 and 6, when full pressure is applied thereto and the units are compressed sufficiently, all of the conducting members 17 will come into contact

thereby in effect, short-circuiting the entire device.

In some ways the modification shown in Figs. 5 and 6 is preferable to silver plating or metal coating such as is shown in the prior figures in that the construction is more rugged and reliable in that the metal coating might sometimes break off or rub thin enough to provide a relatively poor conducting path. However, the relatively rugged and large cross-section member 17 insures a relatively low resistance conductor between opposite contact faces of the unit.

While I have shown and described a particular embodiment of my invention, it will be obvious to those skilled in the art that changes and modifications may be made without departing from my invention and I, therefore, aim in the appended claims to cover all such changes and modifications as fall within the true spirit and scope of my invention.

What I claim as new and desire to secure by Letters Patent of the United States, is:

1. A unit for a compressible resistance, said unit permanently having electrically parallel high and low specific resistance sections respectively between opposite contact faces.

2. A unit for a compressible resistance, said unit having two external contact faces between which there is a relatively high resistance, and means having a relatively low specific resistance permanently connecting portions of said faces.

3. A unit for a compressible type variable resistance, said unit having two contact faces between which there is appreciable resistance, and means for permanently short-circuiting the resistance between fixed portions of said faces.

4. A resistance unit for a pile type resistance, said unit having opposite external faces between opposite points of which there is an appreciable electrical resistance, and a metal coating on said unit for electrically connecting portions of said opposite faces of said unit.

5. A unit for a compressible pile resistance, said unit having opposite external faces of which one is concave, and a relatively low specific resistance electrical conductor joining the center portions of the said faces.

6. A unit for a compressible pile resistance, said unit having a non-uniform effective thickness and a relatively low specific resistance conductor joining the portions of its external faces at the place of minimum thickness.

7. A unit for a compressible pile resistance, said unit having opposite external faces between which its effective thickness varies as measured between parallel plane surfaces, the portions of said faces between which the effective thickness of said unit is a minimum being electrically connected by a relatively low specific resistance electrical conductor.

8. A resistance unit for pile type resistances, said unit having a pair of external contact surfaces one of which is progressively deformable into a given shape by the application of pressure to said unit, and a substantially zero resistance conducting path connecting the portions of said deformable contact surface which last conform to said given shape with the other contact surface.

9. A resistance unit for compressible type resistances, said unit being composed of resilient resistance material having a pair of opposite external contact surfaces one of which is progressively deformable into a given shape by the application of pressure to said unit, and a substantially zero resistance conductor connecting

the portions of said deformable contact surface which last conform to said given shape with the other contact surface.

10. An elongated carbon pile plate, said plate having opposite faces of which one is concave, and a band of relatively low resistance material encircling said plate at its middle portion.

11. A rectangular carbon plate having a pair of opposite contact faces, one of said faces being concave, and a ring of metal coating encircling said plate at its middle portion.

12. A compressible resistance device comprising a plurality of deformable units each having high and low specific resistance sections between opposite contact faces, said units having normally non-parallel adjacent contact faces, and means for compressing said units in such a manner that at low pressure the high specific resistance sections are in contact with each other while the low specific resistance sections are out of contact with each other and at high pressure the low specific resistance sections are in contact with each other.

13. In combination, a plurality of electrical conducting elements arranged in a pile, said elements having normally non-parallel cooperating contact faces, one of said elements being composed of elastic material, one of said elements being composed of electrical resistance material, means for applying pressure to said pile whereby said elastic element is deformed in such a manner that the cooperating contact faces are progressively brought into substantially complete engagement, and a relatively low specific resistance electrical conducting means connecting the portions of the opposite contact faces of said element of resistance material which are substantially the last to come into engagement with cooperating contact faces.

14. A variable resistance device including, in combination, a plurality of electrical conducting plates arranged in a pile, said plates having normally nonparallel adjacent contact faces, one of said plates being composed of deformable resistance material, means for applying pressure to said pile in such a manner that the opposite contact faces of said deformable plate come progressively into substantially complete contact with their adjacent contact faces, and relatively low specific resistance electrical conducting means connecting the portions of the opposite contact faces of said deformable plate which are substantially the last to come into contact with adjacent faces.

15. A carbon pile resistance having, in combination, a plurality of carbon plates arranged in a pile, said plates having normally non-parallel cooperating contact faces, means for applying pressures to said pile whereby said plates are progressively deformed until the cooperating contact faces thereof are in substantially complete contact, and relatively low specific resistance electrical conducting means connecting the points on opposite faces of each plate which are the last points of said faces to contact with cooperating faces.

16. A resistance unit for a pile type resistance, said unit having opposite external faces between opposite points of which there is an appreciable electrical resistance, and a metal conductor extending through said unit from one of said faces to the other, the ends of said conductor forming parts of said contact faces.

17. A carbon resistance unit for a compressible pile type resistance, said unit having opposite external contact faces between which there is an

- appreciable electrical resistance, and a relatively low specific resistance flat-headed metal rivet passed through said unit between said contact faces.
- 5 18. An elongated carbon pile plate, said plate having opposite contact faces of which one is concave, and a relatively low specific resistance metal conductor which is passed through said plate between said faces at the middle portion 10 thereof.
- 10 19. A rectangular carbon plate having a pair of opposite contact faces, one of said faces being concave, and a silver rivet passed through said plate between said faces at the middle portion 15 thereof.
- 15 20. A pile type variable resistor comprising a plurality of resistance units having portions of adjacent contact faces out of contact with each other when minimum pressure is applied to said pile, separate relatively low resistance conducting means carried by each of said units for interconnecting the out of contact portions of their respective contact faces, and means for applying pressure to said pile so that said separate low 20 resistance conducting means are brought into contact with each other.
- 20 21. A pile type variable resistor comprising a plurality of resistance units of the same relatively high contact resistance material having portions of adjacent contact faces out of contact with each other when minimum pressure is applied to said pile, separate relatively low resistance conducting means carried by each of said units for interconnecting the out of contact portions of their respective contact faces, and means for applying pressure to said pile so that said 25 separate low resistance conducting means are brought into contact with each other.
- 25 22. A variable resistance comprising a pile of carbon resistance units having portions of adjacent contact faces out of contact with each other when relatively low pressure is applied to said pile, separate relatively low resistance conducting means passed through each of said units between the out of contact portions of their respective contact faces, and means for applying pressure to said pile so that said separate low resistance conducting means are brought into contact with each other.

LOUIS W. THOMPSON. 25
